UNITED STATES PATENT OFFICE.

ROYAL L. BOULTER, OF LOS ANGELES, CALIFORNIA.

MECHANISM FOR SHARPENING RAZOR BLADES.

Application filed August 20, 1919. Serial No. 320,040.

To all whom it may concern:

Be it known that I, ROYAL L. BOULTER, a citizen of the United States, residing in the city of Los Angeles, county of Los Angeles, 5 and State of California, have invented certain new and useful Improvements in Mechanism for Sharpening Razor Blades, of which the following is a specification.

Among the salient objects of my invention are; to provide improved mechanism adapted to hold a razor blade in yielding and adjustable contact with a moving sharpening surface; to provide in a mechanism of the character referred to, means for automatically moving said razor blade holder longitudinally of the blade and crosswise of said moving sharpening surface, together with means for swinging said holding mechanism from one side to the other, whereby to move the blade so as to cause its opposite sides to alternately engage the moving sharpening surface; to provide a plurality of endless sharpening members or elements with driving means therefor, together with 10 means for adjusting the same to different angles, relative to each other and to the opposite sides of the razor blade holder; to provide means for yieldably supporting the razor blade holder, whereby it can turn 15 about its longitudinal axis for the purpose of permitting the blade to automatically adjust itself so that its edge will contact uniformly with the surface of the moving sharpening element; and to provide in a 20 mechanism of the character referred to means for automatically and intermittently moving said razor blade holder through its different movements, whereby to get a uniform and rapid sharpening action on the 25 razor blades. Other advantages and improved features of construction will be apparent from the following detailed description of one embodiment of my invention, taken in connection with the accompanying 30 drawings, illustrating the same, and in which:

Fig. 1 is a top plan view thereof;

Fig. 2 is a horizontal sectional view thereof;

50 Fig. 3 is a side elevation thereof, with parts broken away and omitted to further show the construction and arrangement;

Fig. 4 is a vertical sectional view longitudinally thereof;

55

Fig. 5 is an end view thereof;

Fig. 6 is a transverse vertical sectional view thereof;

Fig. 7 is an end view looking at the opposite end from that shown in Fig. 5;

60

Fig. 8 is a transverse sectional view;

Fig. 9 is an enlarged top plan view of the blade holder in place in the holding bracket therefor, with a part of the handle broken off to reduce the size of the figure;

Fig. 10 is a fragmentary side elevation of 65 the same;

Fig. 11 is a horizontal sectional view thereof, taken on line 11—11 of Fig. 10;

70

Fig. 12 is a vertical sectional view taken on line 12—12 of Fig. 9;

Fig. 13 is a front end view of said razor holder and bracket, as shown in Fig. 10;

Fig. 14 is a rear end view with parts shown in section;

Fig. 15 is a detailed sectional view taken 75 on line 15—15 of Fig. 9;

Fig. 16 is a similar view taken on line 16—16, of Fig. 9;

Fig. 17 is a sectional view taken on line 17—17 of Fig. 9;

Fig. 18 is a sectional view taken on line 18—18, of Fig. 10;

Fig. 19 is a top plan view of the oscillating mechanism apart from the rest of the machine;

Fig. 20 shows in full lines and in dotted lines various positions of movement of said parts; and

Fig. 21 is a sectional view taken on line 21—21 of Fig. 20.

Referring now more in detail to the drawings, my invention as here illustrated, comprises a box 1, having a cover 2, said cover 2 and a flange 3, at one end of the box being extended, as indicated at 4, and provided with open notches, 5, 5. This end of the box is also provided with supporting lugs 6, 6, between which is supported a plate 7, provided at its lower end with an adjustment screw 8, the inner end of which has 100 a bearing on the end of the box, as at 9, whereby said plate 7, can be adjusted to and from the box 1. Secured to said plate 7, is a motor 10. Mounted across said box,

in suitable supporting bearings in the opposite sides thereof, are two shafts 11 and 12. Shaft 11 is provided with a driving pulley 13, driven by a belt 14 from the motor 10. Said shaft 11 is provided, within the box, with a gear 15 and with a worm 16. The shaft 12 is provided with a large gear 17, which meshes with the gear 15, within said box, and is driven therefrom. 5
10 Also mounted on said shaft 12, are two bevel gears 18 and 19, and an eccentric cam 20. A supporting bracket 21, across the inside of said box 1, supports a worm gear 22, in mesh with the worm 16, on the shaft 11, as 15 clearly indicated in Figs. 2 and 4. Said gear 22 is provided with a shaft 23, provided at its upper end with a crank 24; the outer end of which is provided with a roller 25, for a purpose hereinafter referred to. 20
25 A supporting bracket 26 hooks over the upper top edges of the box 1, at opposite sides, as indicated in Fig. 6, and forms bearings for the opposite ends of the shaft 12, which carries the gears 17, 18, 19 and the eccentric disc 20. A vertical shaft 27 is mounted on the top of said bracket and carries at its lower end a cam block or box 28, enclosing said cam disc 20, said shaft 27 being mounted to be raised and lowered by 30 said cam 20, as the shaft 12 is revolved. Secured to the upper end of said shaft 27, above the top or cover 2 of said box, is a holding bracket 29, having two vertical spaced arms 30, 30, having V-shaped notches 31, in the upper ends, as clearly shown in Fig. 18. Said shaft 27 is provided at its lower end with a yoke 32, carrying a pin 33 for oscillating said shaft 27, about its longitudinal axis in a manner and for a 35 purpose hereinafter referred to. 40
45 A plate 34 is rotatably supported under the bracket 26, around the shaft 27, on a suitable bearing 35, the rear end of said plate flaring outwardly, as at 34', and provided at its opposite corners with downwardly projecting portions 36, adapted to be engaged, respectively, by the inner ends of two adjustment screws 37, 37, which screws are provided with lock thumb nuts 50 38, 38, at the end of the box 1. Said plate 34 is provided on its under side with two spaced bearing pins 39, (Fig. 4,) connected at their lower ends with a short bar 40, said pins 39, being at the opposite sides of the 55 horizontal pin 33, and operating to move said pin 33 for the purpose of oscillating the shaft 27 and the holding bracket 29 at the upper end thereof. The distance of oscillation is controlled by the thumb screws 60 37, 37. At the forward end of said plate 34, are two guide wings 41, 41, through which project two arms 42 and 43, the rear ends of which are pivotally secured to the rear portion of the plate 34, as at 44, 44, 65 and the forward ends of which rest against

the opposite sides of the roller 25, on the crank arm 24, carried at the upper end of shaft 23. A spring 45 connects said arms 42 and 43 near the guide wings 41, 41, as clearly indicated in Figs. 2, 19 and 20. 70

Also mounted through said supporting bracket 26 and the top 2 of said box, are two vertical shafts 46 and 47, carrying at their lower ends bevel gears 46' and 47', in mesh with the bevel gears 18 and 19, and provided at their upper ends with rollers 48 and 49, said rollers being driven in opposite directions, as will be clear from the driving connections indicated in Fig. 6. 75
80 Adjustably mounted at the opposite end of the top of said box, are two similar rollers 50 and 51, said rollers being adjustably supported by flanged bearings 52, which are clamped together against the upper and lower surfaces of the extension 4 of said cover and box, in the open slots 5, 5, by means of bolts 53. Mounted on the rollers 48 and 50, is an endless sharpening element or strop 54. A similar sharpening element or strop 55 is mounted on the rollers 49 and 51, as clearly indicated in Fig. 1. 85
90

Adjustably mounted in the top 2 of said box 1, between the rollers 48 and 50, is an adjustment roller 56, carried by a slotted bar 57, anchored to said top 2, as indicated at 58, whereby said roller 56 can be adjusted longitudinally at the top and also transversely thereof, for the purpose of determining the angle of the sharpening element or strop 54, between the rollers 48 and 56. 95
100 A similar adjusting roller 59, on a slotted bar 60, adjustably anchored, as at 61, is mounted between rollers 49 and 51, for adjusting the angle of the sharpening element or strop 55 between the rollers 49 and 51. 105
110 The tension of the sharpening elements 54 and 55, is regulated by the adjustment of the rollers 50 and 51, in the slots 5, 5, of the top 2. The angles of the portions of said sharpening elements or strops 54 and 55, at their place of engagement with the razor blade, is determined by the adjustment of the rollers 56 and 59. Said endless sharpening elements 54 and 55 are driven in opposite directions by the rollers 48 and 49, 115 which are driven from the bevel gears 18 and 19, as hereinbefore described, the adjacent laps of said sharpening elements moving in the same direction.

Referring to Fig. 6, one of the rollers for the sharpening elements or strops is shown in section to illustrate the construction thereof. The hub portion 48^a, receives the cylindrical portion 48, which is secured thereto by means of bolts, as 48^b. The top 125 of the cylindrical portion is formed with an oil well 48^c therein, with a cap 48^d therefor, held in place by means of a spring 48^e. Thus the cap or cover 48^d can be pulled back to permit oil to be supplied to the inside of 130

said rollers. The hub 48^a is also provided with a cup portion 48^b.

Oil rings R are also provided for the shafts 11 and 12, as seen in Figs. 3, 4 and 6, which carry oil from the oil supply in the box 1 to the shafts and bearings on which they are mounted.

The top 2 is provided with an opening 2^a which is coextensive with the bracket or frame 26 which carries the shafts 46, 47 and 27, whereby to facilitate the removal of these shafts and their bearings.

I will next describe the holder for the blade to be sharpened.

Referring to Figs. 9 to 18, inclusive, said member comprises a bar 62, provided intermediate its ends with a collar 63, secured thereto, and at a space therefrom with a second collar 64, movably mounted thereon and adapted to normally bear against a handle 65. A spring 66 normally moves said collar 64 rearwardly against the handle 65. The forward end of said bar 62 is threaded and is provided with a conical thumb nut 67. To the forward end of said bar 62, is secured a block 68, by means of set screws 69, 69. Pivotally attached to the opposite sides of said block 68, are two jaw members 70 and 71, the forward end of which are adapted to receive therebetween the razor blade to be sharpened. A small expansion spring 72 normally moves said jaws apart. The rear ends or extensions 70' and 71', of said jaws bear against the conical thumb nut 67, whereby the adjustment of said thumb nut 67 forwardly on the bar 62, forces said jaw members 70 and 71 closed, while the adjustment of said conical thumb nut 67 rearwardly, permits said jaws to be opened by the spring 72. Said holder is placed in the holding bracket 29, by inserting it between the arms 30, 30, of said bracket, in the forks at the upper ends thereof, with the conical collars 63 and 64 bearing against the inner or adjacent sides of said arms 30, 30, as clearly indicated in Fig. 9. The spring 60 yieldingly holds said collars 63 and 64, in bearing engagement with said arms 30, 30, which are also beveled to fit the same, as indicated, thus the holder for the razor blade is oscillated with said holding bracket 29, about the axis of the supporting shaft 27, for said bracket 29, and said razor holder itself can be turned about the axis of the bar 62, in the arms 30, 30, to permit the blade held between the jaws 70 and 71 to bear uniformly upon the flat moving sharpening elements or strops 54 and 55, as will be clear from Fig. 1.

The use and operation of my invention may be briefly described as follows:

The razor blade, whether of the safety razor type, or other kind of blade, is clamped between the jaws 70 and 71, in a manner which will be very clear from the

showing. The holder with the blade therein is then applied to the holding bracket 29 by inserting the collar 64 into the rear arm 30 of said bracket, pulling the handle and bar 62 rearwardly and compressing the spring 66 until the collar 63 can be moved down into the beveled seat of the forward arm 30 of said bracket 29, as clearly indicated in Figs. 3 and 9. The blade then is resting between the inner and adjacent laps of the sharpening elements or strops 54 and 55, as clearly indicated in Fig. 1, the blade being indicated in dotted lines. The motor is driving the pulley 13, which in turn drives the shaft 11, the gear 15, and the worm 16. The shaft 12, with its beveled gears 18 and 19, and the eccentric cam disc 20, is also being driven from the gear 17, which is in mesh with the gear 15. The vertical shafts 46 and 47 are also being driven by the beveled gears 18 and 19, and with these shafts the rollers 48 and 49 are driven in opposite directions, and drive the sharpening elements or strops 54 and 55. The eccentric cam 20 is raising and lowering the shaft 27, which carries the razor blade holding bracket 29. This moves the blade up and down longitudinally, and across the faces of the strops 54 and 55. The worm 16, through its connections is driving the crank arm 24, which crank arm with its roller 25, operates the arms 42 and 43, on the plate 34, for the purpose of intermittently turning said plate and the shaft 27 for swinging the bracket 29, with the blade holder, from one side to the other. This operation will be understood more clearly by reference to Figs. 19 and 20. In Fig. 19, the parts are shown in their normal positions, which would leave the razor holding bracket 29 in straight alinement, as shown. As the crank arm 24 turns upwardly to the position indicated in full lines in Fig. 20, it rocks the plate 34, together with the holding bracket 29, to the position indicated in Figs. 20 and 11, until said plate 34 is stopped by the upper set screw 37 in said Fig. 20. The continued rotation of said crank arm 24 moves the arm 43 to the dotted line position, and until the roller 25 on the crank arm swings on around and the arm 43 is retracted by the spring 45 again to its position shown in full lines in Fig. 20, at which time, the roller 25 engages the arm 42 and rocks the plate 34 in the opposite direction, and to the position indicated in dotted lines, and until it engages the lower stop 37. The continued downward swing of the crank arm 24 is permitted by the swinging of the arm 42, independently of any further movement of the plate 34, until said crank 24 returns again, to its normal position. Thus the carrying bracket 29 for the blade holder is moved vertically several times in each posi-

tion. This moves the blade vertically, or crosswise of the sharpening element or strop, several times between the swinging movements from one strop to the other.

5. The machine runs continuously, the carrying bracket 29 for the blade holder being reciprocated vertically with each revolution of the eccentric cam disc, and said carrying bracket being oscillated about its vertical 10 axis, or the shaft 27, with each full turn of the crank arm 24, which is driven by the worm 16. Thus one side of the razor blade is moved repeatedly across the surface of one strop, and is then swung to the other strop, 15 and its opposite side is moved repeatedly in a similar manner across the other strop. This gives rapid sharpening action, for both strops or belts are being continuously driven.

I am aware that many changes in details 20 can be made in my invention as here shown for purposes of illustration without departing from the spirit thereof, and I do not, therefore, limit the invention to the showing made, except as I may be limited 25 by the hereto appended claims.

I claim:

1. In a machine for sharpening razor blades, a housing with motor, shafts through the side of said housing with gears thereon 30 within said housing, with means to be driven from said motor, vertical shafts through the top of said housing with gears in mesh with the gears on said first shafts, driving pulleys on the shafts through the top of said 35 housing, to be driven thereby, two endless sharpening elements mounted on said pul-

leys to be driven thereby, with adjacent laps of said sharpening elements running in the same direction, means for changing the angle of direction of said sharpening elements at 40 positions opposite each other, a razor blade holder, and supporting and operating means for holding said blade holder between the adjacent laps of said sharpening elements, with means for raising and lowering the 45 same intermittently and automatically and for oscillating it from one side to the other between the adjacent sides of said sharpening elements.

2. In a machine of the character described, 50 a casing, a shaft in said casing with gears and an eccentric thereon, shafts through the top of said casing and connected to be driven from within said casing, endless sharpening elements driven by said shafts on top of said casing, a blade holder operatively supported from said eccentric, through the top of said casing, whereby it is moved up and down across the faces of said sharpening elements, and means for oscillating said blade holder 55 about its supporting axis to swing the blade holding end thereof from one sharpening element to the other, and means for driving said various elements together, substantially as shown and described.

Signed at Los Angeles, county of Los Angeles, and State of California, this 8th day of August, 1919.

ROYAL L. BOULTER.

In presence of:—

W. R. LITZENBERG,
H. M. BRUNDAGE.
